US00D915464S

(12) **United States Design Patent** (10) Patent No.: **US D915,464 S**
(45) Date of Patent: ** Apr. 6, 2021

(54) **DISPLAY SCREEN OR PORTION THEREOF WITH A GRAPHICAL USER INTERFACE**

(71) Applicant: **VITALCHAINS CORPORATION**,
Menlo Park, CA (US)

(72) Inventors: **Feng-Shuen Huang**, Taoyuan (CN);
Yi-Ting Huang, Zhubei (CN)

(73) Assignee: **VITALCHAINS CORPORATION**,
Menlo Park, CA (US)

(**) Term: **15 Years**

(21) Appl. No.: **35/506,951**

(22) Filed: **Sep. 4, 2018**

(80) **Hague Agreement Data**

Int. Filing Date: **Sep. 4, 2018**

Int. Reg. No.: **DM/201476**

Int. Reg. Date: **Sep. 4, 2018**

Int. Reg. Pub. Date: **Jun. 21, 2019**

(51) **LOC (13) Cl. 14-04**

(52) **U.S. Cl.**

USPC **D14/492**

(57) **CLAIM**

The ornamental design for a display screen or portion thereof with a graphical user interface, as shown and described.

DESCRIPTION

Display screen or portion thereof with a graphical user interface

Reproduction 3.1 is a front view of a display screen or portion thereof with a graphical user interface.

The outermost broken line showing a display screen or portion thereof, as well as all broken lines therein showing portions of the graphical user interface, are included for the purpose of illustrating portions of the article and form no part of the claimed design.

1 Claim, 1 Drawing Sheet
